UNITED STATES PATENT OFFICE.

HERBERT ALFRED HUMPHREY, OF LONDON, ENGLAND, ASSIGNEE TO HUMPHREY GAS PUMP COMPANY, A CORPORATION OF NEW YORK.

METHOD OF RAISING OR FORCING LIQUID.

1,214,791.

Specification of Letters Patent. Patented Feb. 6, 1917.

Application filed July 22, 1911, Serial No. 639,972. Renewed June 27, 1916. Serial No. 108,281.

To all whom it may concern:

Be it known that I, HERBERT ALFRED HUMPHREY, a subject of the King of Great Britain, residing in London, England, have 5 invented a new and useful Method of Raising or Forcing Liquid, of which the following is a specification.

My invention relates to internal combustion pumps and compressors, in which a 10 column of liquid is propelled outwardly from a combustion chamber by an expansive force, whereby a fresh expansible charge is introduced, and in which a column of liquid flows inwardly toward a combustion chamber whereby the charge is compressed.

The object of my invention is to provide an improved method whereby the kinetic 20 energy of the outwardly propelled column of liquid may be utilized in introducing a fresh expansible charge. I may also introduce fresh scavenging air before the burnt products are expelled.

Referring to the accompanying drawings, illustrating merely by way of example, apparatus for effecting the improved method herein described, Figure 1 is a diagrammatic vertical section. Fig. 2 is a detail in vertical section on an enlarged scale of an inlet valve. Fig. 3 is a fragmentary vertical 30 section showing modification in combustion chamber and inlet and exit valves. Fig. 4 is a vertical section showing other modifications. Fig. 5 is a vertical section showing further modifications in combustion chamber and inlet and exit valves and also showing a free piston interposed between the charge and the liquid. Fig. 6 is a vertical section showing means and method for introducing gas and air by movements in the super- 35 40

Similar numerals refer to similar parts throughout the several views.

I find that it is possible to introduce into the combustion chamber a fresh combustible 45 charge before the exhaust gases have been expelled from the chamber, without pre-ignition. Moreover, whether the combustible charge is drawn in by partial vacuum or introduced under sufficient pressure to produce displacement, such charge may be introduced in such a way that the combustible mixture and the exhaust gases are kept separate or sufficiently separate until the bulk 50 of the exhaust gases is expelled. For avoiding pre-ignition and for preventing inter-

mixing as far as possible, the combustion chamber should be suitably shaped and the inlet and exhaust valves suitably arranged relatively to each other; for the same purpose the combustible charge may be preceded by a quantity of air.

The following is an example of the working cycle which may be obtained:—Ignition of a compressed combustible charge followed by expansion of the burnt products 60 and the intake of a fresh combustible charge (accompanied or not by the intake of fresh liquid) during the outstroke of the liquid column. During the instroke of the liquid column burnt products are first expelled and 70 then the fresh combustible charge compressed ready for ignition to start a fresh cycle. If the scavenging air or the combustible charge or both are supplied under slight pressure, then they can begin to enter 75 as soon as the burnt gases have expanded approximately to atmospheric pressure and continue to enter until the instroke of the liquid column closes the exhaust valve. One of the advantages of this cycle arises from 80 the fact that there need be no locking gear between the inlet and exhaust valves, and this renders the use of a number of inlet and exhaust valves an easy matter so that large valve areas may be employed. High compression pressures may also be obtained, 85 since during its instroke the liquid column may gain velocity while driving out the gaseous contents of the combustion chamber until the exhaust valve closes, and compression of the fresh combustible charge begins. Again, certain portions of the combustion 90 chamber may be maintained comparatively hot and dry, and such hot portions may be conveniently used in connection with the use 95 of liquid fuels which require to be vaporized.

In Fig. 1, 1 is the main body of a combustion chamber, circular in plan, the upper part 2 of which is annular and closed except for a ring of admission valves two 100 of which, 3 and 3^a are shown. At a lower level are exhaust valves 4 adapted to open by their own weight and to be closed by the action of the liquid when it reaches them. Nonreturn valves 5 situated in a partition 6 105 allow burnt gases to pass into the exhaust pipe 7 but not to return, and such valves may be made very light so as to open under the action of slight pressure and to close under the action of their own weight. A 110

bend 8 connects chamber 1 with an inlet valve box 9 fitted with inlet valves 10 for liquid, and 9 is in turn connected with the play pipe 11 which leads to a place of higher level or pressure and in which the liquid column reciprocates. A tank 12 contains the liquid to be raised and is fed with fresh liquid through inlet 13. Considering first only those parts already mentioned and assuming that valves 3, 3^a are normally held closed by light springs which allow the valves to open under suction and admit combustible mixture, one method of operating is as follows: A compressed combustible charge is ignited in the top of 2 and expansion occurs driving liquid downward in chamber 1 and outwardly along pipe 11 so that the liquid column therein attains considerable kinetic energy. Suppose that the expanded gases attain atmospheric pressure when the liquid level is at *a a* in chamber 1. The liquid column in 11 is then moving with considerable velocity and valves 10 open and admit more liquid into 9 to follow the moving liquid. Exhaust valves 4 open under their own weight but the suction which occurs in chamber 1 cannot draw in exhaust products since valves 5 prevent this, but the continued movement of the column of liquid lowers the level to *b b* and causes the intake of combustible mixture through valves 3, 3^a, so that the incoming mixture occupies the space in 2 down to the level say of *c c*, displacing the burnt products from this part of the chamber. The volumetric change represented by the fall of liquid from *a a* to *b b* can be controlled by altering the level of liquid in tank 12 which for the present is regarded as an open top tank. If the level of liquid in 12 is raised then the tendency of liquid to flow from 12 into chamber 1 is increased and the volumetric change in 1 is diminished. Conversely, if the level of liquid in 12 is diminished the volumetric change is increased and thus by such control the combustible charge taken into 2 can be made to occupy the space approximately to the level *c c*. When the liquid column has come to rest the suction in chamber 1 ceases and valves 3, 3^a close under the action of their springs. A return movement of the column now begins under the action of a head or pressure and, valves 10 having also been closed by their springs, liquid rises in 1, drives out burnt gases through valves 4, shuts these valves and compresses the combustible charge in the upper portion of the chamber until the column of liquid again comes to rest. Ignition of the charge then starts a fresh cycle.

It being desirable that the fresh combustible charge should be introduced in such manner as to prevent it mixing with the burnt products present and also to prevent loss of combustible gas through valves 4,

the combustion chamber should be shaped with this end in view. Thus in Fig. 1 the annular shape of the part 2 of the chamber and the use of a number of admission valves is adapted to secure the desired result and it is preferable to let in air only at first and then mixture. If alternate admission valves are connected with air and gas supplies respectively then the weight of valve and strength of spring for each class of valve can be so proportioned that the air valves open first when suction occurs.

If all the valves admit mixture, they can be constructed as shown, drawn to an enlarged scale, in Fig. 2 so that the first part of the opening movement gives passage for air only, while further opening admits both gas and air. Thus the valve 63 controls both the air port 14 and the gas port 15. It will be evident that air is admitted so soon as the valve leaves its outer seat, and only after it has moved distance *d* will gas be admitted.

Fig. 3 shows another form of combustion chamber where the combustible gases are admitted into a central portion 2 and the exhaust valves are in a ring below 2 as shown. Light nonreturn valves 5 are carried on the stems of valves 4. Corresponding parts are numbered to agree with Fig. 1 and the cycle of operations is the same.

To obtain more uniform action and the benefit to be derived from measuring into the chamber a definite combustible charge the complete arrangement shown in Fig. 1 may be adopted and the parts not yet referred to will now be described.

The tank 12 is closed by an air tight top 65 and the sides extended to form a second tank 16 containing liquid in which two small holders 17 and 18 for gas and air respectively may rise and fall. The outer holder 18 is annular and the holder 17 is co-axial with it, and arranged so that when the outer holder rises it carries the inner holder with it by engaging flange 19. In the closed tank 12 there is an air inlet 20 fitted with a hinged valve 21 and air is drawn in through this valve each time the level of the liquid in tank 12 falls, but when the level of the liquid rises air is forced through pipe 22 past non-return valve 23 into the holder 18, thus causing the holder to rise. An inlet 24 for gas communicates with pipe 25 and holder 17 and gas flows or is drawn into 17 through pipe 25 and valve 26 as 17 rises, or is lifted by the movement of holder 18.

Outlet pipes 27 and 28 for gas and air respectively lead to separate ring mains 29 and 30, which supply the admission valves 3 and 3^a. When there is a ring of such valves, one set of valves as 3^a, is supplied with gas and the other set as 3, alternately arranged is supplied with air. This secures that there shall be no explosive mixture outside chamber 1.

In the gas pipe 27 there is a throttle valve 31 operated by a lever 32, one end of which is acted upon by a spring 33 to close the valve and the other end is adapted to be 5 acted upon by a weight 34 to open the valve. A cord 35 attached to the holder 18 at 36 and to the weight 34 is carried by pulleys 37 pivoted at 38 and the length is adjusted so that when the holder 18 is in its highest 10 position valve 31 is closed by spring 33, but, in falling, weight 34 is lifted and by contact with lever 32 valve 31 is opened. Thus for example when holder 18 falls half way valve 31 may be opened and maintained open 15 for the rest of the fall.

The fall of the liquid level in tank 12 is caused by the sudden intake of liquid through valves 10 which occurs toward the end of the working stroke of the pump, and 20 the rise is due to the fresh supply of liquid entering the tank through pipe 13 during the period intervening before the next intake. The operation may begin with the ignition of a compressed combustible charge 25 in chamber 1 and as already explained atmospheric pressure is attained when the gases have expanded to *a a*. At this time the level of liquid in tank 12 is about at its highest and so there is least air in tank 12 30 and most air in holder 18 which is in its highest position. The pressure of air in holder 18 aided by the further fall of liquid in chamber 1 to *b b* causes air to flow from the holder past valves 3 into the chamber 35 and by introducing sufficient air burnt products may be displaced and driven out past valves 4 so long as these valves remain open, and while the liquid is first falling and then rising in chamber 1. Now until 40 holder 18 has fallen far enough to cause the opening of valve 31 the gas holder 17 cannot fall, but beyond this point both holders fall together and supply gas and air to chamber 1 to intermingle therein and to 45 form a combustible mixture in the top thereof. The inflow of the mixture may continue until the liquid rising in chamber 1 reaches valves 4 and shuts them and the 50 period of inflow may thus cover that part of the cycle in which the moving liquid column in play pipe 11 slows down and comes to rest and then moves a considerable portion of its stroke in the reverse direction, which period occupies the greater portion of 55 the time of a complete cycle. For this reason sufficient air can be introduced to effect scavenging and can be followed by the inflow of the combustible constituents without using any pressures beyond what are com- 60 monly employed in gas holders. Between the closing of valves 4 and their next opening the liquid level in tank 12 rises and so forces a fresh supply of air through pipe 22 into holder 18 thus lifting both holders 65 which become charged again ready for the

next cycle. The tendency of liquid to flow from tank 12 into chamber 1 when the level in the former is the greater must not be overlooked.

For the movable gas holders of Fig. 1 70 may be substituted a fixed device for introducing the gas and air. Such a device is shown in Fig. 4 where the rise and fall of the liquid in the delivery tank is used instead of that in the supply tank. The 75 play pipe 11 is connected with a conical delivery tank 40 having an outlet 41 for the liquid raised. The tank has a closed top from which a partition 42 extends downward below the minimum liquid level *l l*. 80 This divides the space above the liquid into two parts 43 and 44 used for gas and air respectively. The gas enters through pipe 45 which is carried vertically downward in the tank to level *l² l²*, and has a branch as 85 shown fitted with a hinged valve 46. The outlet for gas is pipe 47 which is connected with ring main 29 supplying the combustion chamber 1. Air enters the top of the tank through pipe 48 which extends downward 90 to the level *l' l'* and carries a branch fitted with hinged valve 49. Pipe 50 conveys the air to ring main 30 above chamber 1.

The action of this part of the apparatus is as follows: When ignition occurs in chamber 1 the level of liquid in 40 is at its lowest, that is at *l l*. Liquid is driven along the play pipe 11 into tank 40 where the level rises to *l' l'* by the time the burnt gases attain atmospheric pressure and exhaust 100 valves 4 open. The rise of liquid from *l l* to *l' l'* displaces air from 44 through pipe 48, but further rise past the bottom of this pipe cuts off the escape of air through 105 48 and forces it through pipe 50 into ring main 30, and so past the air inlet valves 3 into chamber 1, thus displacing burnt products in the chamber. In like manner, but starting a little later, the gas in 43, some of which has been driven back through pipe 45 as 110 the liquid rises from *l l* to *l² l²*, is forced through pipe 47 into chamber 1; and during the change of level from *l² l²* to the highest level *l³ l³*, gas and air are delivered together 115 into the combustion chamber. Valves 3 and 3^a now close and the level of liquid falls in tank 40 partly due to the continuous delivery through 41, and partly to the movement of the liquid in the play pipe, when the liquid column returns to shut valves 4 and 120 compress the fresh combustible charge.

During the fall of the liquid, nonreturn valves 46 and 49 provide inlets for gas and air respectively until the bottoms of pipes 45 and 48 are uncovered by the liquid, and 125 when the lowest level *l l* is again reached 43 and 44 are again charged ready for a repetition of the cycle.

In the previous examples the combustible mixture is drawn in at the top of the com- 130

bustion chamber and the burnt products are displaced downward, but as these products, being heated, have a lower specific gravity than the incoming air and combustible mixture or gas, it is sometimes desirable to displace them upward. This can be effected by the arrangement shown in Fig. 5 where 1 is the combustion chamber having the exhaust valve 4 above the valves 3 and 3^a for the admission of combustible constituents. In this case the known device of a rigid piston 51 resting upon the end of the liquid column is used, and carries a rod 52 supported by a spring 53 carried in a tubular projection 54 attached to the piston. Rod 52 is adapted to engage against valve 4 and to close this valve when the piston rises far enough in the combustion chamber. It is obvious that a float attached to valve 4 by a rod may be substituted for the piston. Valve 5 serves the same purpose as the valves 5 in the other constructions.

The method of operation is as follows: Ignition occurs when the piston 51 has risen and compressed a combustible charge in the top of chamber 1 and all valves are shut. As expansion proceeds and atmospheric pressure is attained, piston 51 uncovers the outlet of valves 3 and 3^a and valve 4 opens but valve 5 is closed. The further downward movement of the piston along with the water column permits the intake of combustible constituents through valves 3, 3^a, until the piston and water column come to rest and valves 3, 3^a are shut. The return movement of the water column then lifts the piston, driving out the burnt products, which in this case are on top, ejecting them past valves 4 and 5, until rod 52 reaches valve 4, and shuts it. The further movement of the piston compresses the fresh combustible charge in the top of chamber 1, and the ignition of this charge starts a fresh cycle. Rod 52 should be of such length as to close valve 4 as soon as the products are nearly expelled, so that little or no combustible mixture may be lost. It will be observed that the valves 3, 3^a are situated in recesses so that piston 51 may rise past them. It will also be evident that after the top of rod 52 meets valve 4 and shuts it, the further movement of piston 51 causes spring 53 to be compressed. The cycle is essentially the same in this as in the previously described cases but the combustible mixture is taken in below the burnt gases.

Gas and air may be introduced by movements in the supply liquid in a manner differing somewhat from that described with reference to Fig. 1 as will be explained with reference to Fig. 6 in which corresponding parts are numbered as before. The liquid inlet valves 10 are surrounded by an annular chamber 13^a, forming a closed end to the supply pipe 13, in which is fixed a bell 55

divided by partition 42 into two chambers 43 and 44 adapted to receive gas and air respectively.

Gas enters at pipe 45 which extends downward in the bell and carries at its lower end a valve 56. Air enters at pipe 48 which carries a valve 57. The outlet pipes 47 and 50 for gas and air respectively are fitted with valves 58 and 59 and are connected in this case with a mixture admission valve 3 in chamber 1. All the valves 56, 57, 58 and 59 are normally open under their own weight and are adapted to be closed by the liquid as it reaches them.

The introduction of the gases is effected in the following manner: Suppose the level of the liquid supply is at d , that the supply pipe 13 is long enough for the liquid in it to have considerable inertia, and that chambers 43 and 44 are nearly full of liquid. Ignition and expansion occurs in chamber 1 and when atmospheric pressure is attained valves 10 and 4 open. Liquid rushes in through valves 10 and the first effect is to lower the level in the nearest source of supply namely chambers 43 and 44 since the mass of liquid in pipe 13 cannot be quickly accelerated. Gas is thus taken into chamber 43 through pipe 45 and the air into chamber 44 through pipe 48 while the flow of liquid in pipe 13 is being accelerated and until the supply of liquid in 13 equals the flow through valves 10. The outward movement of the liquid column in play pipe 11 is now decreasing in velocity but the flow in pipe 13 having attained its maximum velocity tends to be maintained by the momentum of the liquid and so the surplus supply of liquid rises in chambers 43 and 44, shuts valves 57 and 56 in turn, and delivers gas and air through pipes 47 and 50 and valve 3 into chamber 1, until the liquid reaching valves 58 and 59 shuts them and is brought to rest by compressing the unjected gas and air entrapped in the tops of chambers 43 and 44.

By suitably proportioning the parts, the delivery of the gas and air may occur wholly or partly during the return stroke of the liquid column in pipe 11, but before the liquid rises in chamber 1 far enough to close exhaust valves 4. In such case an ordinary scavenging valve 60, Fig. 6, for air, is provided and supplies air during the outward stroke of the liquid column.

What I claim is:

1. The method of raising or forcing liquid, which consists in reciprocating a column of liquid, the outstroke of said reciprocation being due to an expansive force, utilizing the movement of the outstroke in introducing a fresh expansible charge and expelling the exhaust.

2. The method of raising or forcing liquid, which consists in reciprocating a column of

liquid, the outstroke of said reciprocation being due to an expansive force, utilizing the movement of the outstroke in introducing a fresh expansible charge and expelling the exhaust, and utilizing the movement of the return stroke to compress said charge.

3. The method of raising or forcing liquid, which consists in reciprocating a column of liquid, the outstroke of said reciprocation being due to an expansive force, utilizing the movement of the outstroke in introducing a fresh expansible charge and expelling the exhaust, and utilizing the changes of level of a liquid supply for controlling the level to which the liquid falls in the expansion space during the outstroke and thus affecting the volumetric intake of the fresh expansible charge.

4. The method of raising or forcing liquid, which consists in reciprocating a column of liquid, the outstroke of said reciprocation being due to an expansive force, utilizing the movement of the outstroke in introducing a fresh expansible charge and expelling the exhaust, and utilizing the changes of level of a liquid supply for controlling the level to which the liquid falls in the expansion space during the outstroke and thus affecting the volumetric intake of the fresh expansible charge and the displacement of the exhaust.

5. The method of raising or forcing liquid, which consists in reciprocating a column of

liquid, the outstroke of said reciprocation being due to an expansive force, utilizing the movement of the outstroke in introducing a fresh expansible charge and expelling the exhaust, after the lowering of the level of the liquid during the instroke has drawn a fresh charge into the space vacated by said liquid.

6. The method of raising or forcing liquid, which consists in reciprocating a column of liquid, the outstroke of said reciprocation being due to an expansive force, utilizing the movement of the outstroke in introducing a fresh expansible charge and expelling the exhaust, and utilizing the change of level of the liquid delivered for displacing the exhaust by introducing the fresh expansible charge.

7. The method of raising or forcing liquid, which consists in reciprocating a column of liquid, the outstroke of said reciprocation being due to an expansive force, utilizing the later period of said outstroke movement to introduce a fresh expansible charge, utilizing the earlier period of the return stroke to discharge the exhaust, and the later period of the return stroke to compress the charge.

HERBERT ALFRED HUMPHREY.
